UNITED STATES PATENT OFFICE

VALENTINE WOJCIECHOWSKI, OF BROCKTON, MASSACHUSETTS

VENTILATED SHOE

Application filed January 6, 1930. Serial No. 418,935.

This invention relates to shoes and more particularly to a shoe having openings formed therein for ventilating purposes.

One object of the invention is to provide a shoe so constructed that air may circulate through the same and thereby prevent a person's feet from becoming cold during the winter and also prevent the feet from becoming overheated and sweating during the sum-
10 mertime.

Another object of the invention is to provide improved means for closing the ventilating openings at their outer ends during wet weather and thereby prevent water from
15 passing inwardly through the ventilating openings and causing a person's feet to become wet.

Another object of the invention is to so form and apply the closure means for the
20 openings to the shoe that it will be neat in appearance and not detract from the appearance of the shoe.

Another object of the invention is to so mount the closure upon the shoe that it may
25 be very easily moved into and out of an operative relation to the ventilating openings and to further cause the closure to remain in a set position when moved to an operative or inoperative position.

30 The invention is illustrated in the accompanying drawings, wherein,

Figure 1 is a perspective view of a shoe provided with ventilating openings and showing the closure for these openings moved to
35 an operative position about the forward end of the toe of the shoe, and

Figure 2 is a sectional view taken transversely through the shoe with the closure moved to an operative position and extending
40 in covering relation to the outer ends of the ventilating openings.

The shoe shown in Figure 1 and indicated in general by the numeral 1 is of a conventional construction and while the shoe illustrated in this figure is of the low quarter type it is to be understood that it merely represents one form of shoe to which the invention may be applied. This shoe includes the usual upper 2 and sole 3. A tip 4 may
50 be secured about the toe portion of the upper

or omitted. Through the toe portion of the upper are formed a suitable number of openings 5 which may be of any size desired and through these openings are passed eyelets 6 of the type usually employed in the lace receiving openings of the shoe. These eyelets not only impart a good appearance to the shoe but also constitute reinforcements about the margin of the openings 5 and prevent danger of tearing the upper between the openings and also reduce likelihood of the openings becoming closed by paste applied to a shoe when shining it. Since the shoe is formed with ventilating openings air may pass into and out of the shoe through these openings and thereby prevent a person's feet from becoming overheated and sweating during hot weather and also prevent the feet from becoming cold during the winter.

In order to close the ventilating openings during wet weather and thereby prevent water from passing inwardly through the ventilating openings and cause a person's feet to become wet, there has been provided a strip 7 formed of rubber which will be colored to correspond to the shoe. Openings are formed near the ends of the strip constituting button holes through which eyelets 8 are passed to serve as reinforcements for the button holes and through these button holes are engaged pins 9 having their inner ends secured through the upper at opposite sides of the shoe close to the sole. These pins or buttons 9 have heads 10 at their outer ends and while the heads are of sufficient size to be passed easily through the openings in the strip the elasticity of the strip will prevent the pins from slipping through the button holes. Therefore, the strip will be retained in engagement with the shoe. Under ordinary conditions the elastic strip is so disposed that it extends forwardly about the front of the toe of the shoe as shown in Figure 1, thereby leaving the ventilating openings exposed and permitting air to pass freely through these openings. It should also be noted that when the strip is in the inoperative position shown in Figure 1 it will serve as a protector for the toe portion of the shoe and prevent the outer surface of the leather from being skinned or otherwise
100

marred in case a person should accidentally strike his foot against a curb or other obstruction while walking. When it is desired to prevent water from passing inwardly through the openings during wet weather it is merely necessary to grasp the strip at the front of the toe of the shoe and by exerting pull, draw the strip rearwardly until it extends transversely across the shoe between the pins and covers the outer ends of the ventilating openings. This position is indicated by dotted lines in Figure 1 and shown in full lines in Figure 2, and by referring to Figure 2 it will be seen that when the strip is in the operative position it fits snugly against the shoe and tightly closes the outer ends of the ventilating openings. When protection against water is no longer necessary the strip is grasped intermediate its ends and can be very easily returned to the inoperative position shown in Figure 1.

Having thus described the invention, I claim:

1. A shoe having its upper formed with ventilating openings in its toe portion, and a closure for the outer ends of said openings extending transversely of the shoe and having its ends pivoted to the shoe at opposite sides thereof whereby the closure may be swung from a position to cover the outer ends of the openings to a position about the front end of the toe of the shoe.
2. A shoe having its upper formed with ventilating openings in its toe portion, and a closure for the outer ends of said openings consisting of a strip of elastic material secured at its ends to opposite sides of said shoe and movable from a position across the upper in covering relation to the openings to a position about the front end of the toe of the shoe.
3. A shoe having its upper formed with ventilating openings in its toe portion, pins extending from opposite sides of the shoe upper adjacent the sole of the shoe, and a strip of elastic material having eyes at its ends receiving said pins to connect the strip with the shoe, said strip being movable about the pins from a position to extend across the upper in covering relation to the outer ends of the openings to a position extending forwardly about the toe of the shoe in snug fitting engagement therewith.

In testimony whereof I affix my signature.

VALENTINE WOJCIECHOWSKI. [L.S.]
